UNITED STATES PATENT OFFICE.

JOHN W. JOHNSON, OF TRENTON, MISSOURI.

BOILER-FLUE.

1,012,258.

Specification of Letters Patent. Patented Dec. 19, 1911.

Application filed February 25, 1911. Serial No. 610,751.

To all whom it may concern:

Be it known that I, JOHN W. JOHNSON, a citizen of the United States, residing at Trenton, in the county of Grundy and State 5 of Missouri, have invented new and useful Boiler-Flues, of which the following is a specification.

It is the aim of the present invention to provide an improved boiler construction and 10 more specifically speaking the invention resides in a novel manner of assembling the boiler flues with the flue sheets.

Incidentally, it is one object of the invention to counteract, as far as possible, any 15 lengthwise expansion or contraction of the boiler flues such as would tend to force them through the flue sheets or draw them through the same, and to this end, one of the boiler flue sheets is formed with flue end receiving 20 openings around the edges of which are shoulders against which the ends of the boiler flues abut, a packing gasket being interposed between the said ends of the boiler flues and the said shoulders at the edges of 25 the openings. The shoulders in the edges of the openings are formed by counterboring the flue sheets from their inner faces so that the shoulders are presented in the same direction as are the inner faces of the said 30 sheets, and consequently such longitudinal expansion of the flues as would ordinarily result in their being forced rearwardly through the flue sheets is effectually checked or obviated.

Another feature of the invention resides 35 in the provision of a thimble which is fitted into the ends of the flues and which effectually protects the said ends of the flues, the packing gasket, and the edges of the openings into which the ends of the flues are 40 fitted, from such extremes of temperature as would tend to cause abnormal expansion or contraction of the elements mentioned.

In the accompanying drawings, Figure 1 45 is a vertical sectional view showing two flues and two flue sheets with which the flues are assembled, one flue being shown in position prior to the insertion of the protecting thimble thereinto and the other flue being 50 shown completely assembled. Fig. 2 is a view in elevation of a portion of one flue sheet and that end of the flue into which the projecting thimble is inserted, the said thimble being shown in end elevation, and

Fig. 3 is a view similar to Fig. 2 but looking 55 at the opposite end of the flue.

In the drawings, the numeral 5 indicates the rear flue sheet of a boiler and the numeral 6 indicates the front flue sheet thereof or more specifically stated that sheet 60 which forms one wall of the smoke-box of the boiler furnace. The boiler flues are indicated by the numeral 7.

As is clearly shown in Fig. 1 of the drawings, the rear flue sheet 5 is bored with 65 openings 8 which extend entirely through the said sheet and subsequent to the boring of these openings, is counterbored as at 9, the counterbore extending from the forwardly presented face of the sheet inwardly 70 to a point near the rear face of the sheet whereby an annular shoulder 10 is afforded at the edge of each opening 8 in the sheet. Also as clearly shown in the said figure of the drawings, the counterbore 9 is threaded 75 and the rear ends of the flues 7 are also threaded exteriorly as at 11 and the said ends of the flues are, when being assembled with the rear flue sheet 5, threaded into the counterbore 9 in the said flue sheet and 80 abut at their said ends each against a packing gasket 12 which is disposed between the said ends of the flue and the shoulder 10 of the corresponding flue end receiving opening, this packing gasket being preferably of 85 brass although any other material may be employed as may be found expedient. After each flue and its respective packing gasket have been assembled with the rear boiler flue sheet 5, the end of the flue, the said 90 gasket, and the edge of the opening 8 are interiorly rolled so as to present a smooth interior surface and further to slightly expand the flue at the said end thereof and to cause a snug fit of the packing gasket. After 95 the ends of the flues have been rolled as above stated, a thimble 13 is driven into the rear end of each flue and is overturned at its outer end as at 14, in the usual manner, this thimble projecting into the flue to such 100 degree as to cover the interior surface of the flue at the said rear end thereof, the inner edge of the packing gasket 12, and the inner or annular edge of the shoulder 10. It will be understood that by inserting this flue 105 thimble 13 into the end of each flue, the said end of each flue, its respective packing gasket 12, and the edge of the opening in

the boiler flue sheets are all effectually protected from sudden abnormal changes in temperature and that consequently abnormal expansion and contraction of the several elements will not be liable to occur. Furthermore, the thimble protects or tends to prevent to a considerable degree the "burning out" of the flues and gaskets. At their forward ends (their ends which open into the smoke-box of the boiler furnace) the flues 7 project through openings 15 which are formed through the forward boiler flue sheet 6 and at their ends beyond the forward face of the said sheet, they being rolled after their engagement through the sheet whereby to secure a water-tight fit. The said forward ends of the flues are formed each with a plurality of diametrically oppositely disposed notches 16, in which may be engaged a suitable tool which may be rotated for the purpose of rotating the flues to tighten their engagement of their rear ends in the threaded counterbores 9 in the rear flue sheets 5.

From the foregoing description of the invention, it will be understood that as far as the same concerns the manner in which the flues are assembled with the rear flue sheets 5, the abutment of the flue ends against the shoulders 10 or more specifically speaking against the packing gasket which is interposed between their said ends and the said shoulders, insures against longitudinal expansion of the said flues such as would force their said rear ends through the flue sheets and beyond the rear face thereof, the shoulders 10 arresting any such tendency in an effectual manner.

It will further be understood that the flues may be more readily assembled with the flue sheets and at considerably less expense in the manner disclosed in the draw-

ings and heretofore described than by the present methods of assembling in which the ends of the flues are overturned.

It will still further be understood that by forming the forward ends of the flues with the notches 16, means is provided whereby the flues may be quickly and easily tightened.

What is claimed is.

1. In boiler construction, a flue sheet formed with an opening having a shoulder at its edge presented toward the inner face of the sheet, a packing gasket disposed within the opening and against the shoulder, a flue threaded into the opening and abutting at its end against the said gasket, and a thimble pressed into the opening of the sheet beyond the gasket, the outer end of the thimble being spun to cover the rim of the opening in the sheet.

2. In boiler construction, a flue sheet formed with an opening having a shoulder at its edge and presented toward the inner face of the sheet, a packing gasket disposed within the opening and against the shoulder, a flue threaded into the opening and bearing at its end against the said packing gasket, the flue being formed at its opposite end with a plurality of notches, and a thimble pressed into the opening of the sheet beyond the gasket, the outer end of the thimble being spun to cover the rim of the opening in the sheet.

In testimony that I claim the foregoing as my own, I have hereto affixed my signature in the presence of two witnesses.

JOHN W. JOHNSON.
